Primary Examiner — Cynthia Ramirez*Assistant Examiner* — Llorellys Martinez-Rivera(74) *Attorney, Agent, or Firm* — Richard M. Goldberg(57) **CLAIM**

The ornamental design for a wall panel, as shown and described.

DESCRIPTION

FIG. 1 is a top plan view of a first embodiment of a wall panel showing my new design;

FIG. 2 is a bottom plan view thereof;

FIG. 3 is a front elevation view thereof, the rear elevational view being a mirror image thereof, the right side and left side elevation views being identical thereto;

FIG. 4 is a top plan view of a second embodiment of a wall panel showing my new design;

FIG. 5 is a bottom plan view of the wall panel shown in FIG. 4; and,

FIG. 6 is a front elevational view of the wall panel shown in FIG. 4, the rear elevational view being a mirror image thereof, the right side and left side elevation views being identical thereto.

The wall panel is shown with a symbolic break in its length. The appearance of any portion of the wall panel between the breaks forms no part of the claimed design.
